UNITED STATES PATENT OFFICE.

PIERRE HUBERT HOUNGET, OF VONDA, SASKATCHEWAN, CANADA.

HOLDER FOR CIGARS AND CIGARETTES.

1,102,925.

Specification of Letters Patent.

Patented July 7, 1914.

Application filed March 22, 1912. Serial No. 685,474.

To all whom it may concern:

Be it known that I, PIERRE H. HOUNGET, a subject of the King of Great Britain, residing at Vonda, in the Province of Saskatchewan and Dominion of Canada, have invented new and useful Improvements in Holders for Cigars and Cigarettes, of which the following is a specification.

An object of the invention is to provide 10 a cigar and cigarette holder for supporting the cigar or cigarette in smoking position.

The invention embodies, among other features, a device including a mouthpiece and a tubular container adapted to contain the 15 smokable article, a spring being provided for forcing the smokable article outwardly from the container as the article is consumed and a retaining sleeve for connection with the container for retaining the smokable article within the container, against the action of the said spring.

In the further disclosure of the invention reference is to be had to the accompanying drawings which constitute a part of this 25 specification, in which similar characters of reference denote corresponding parts in all the views, and in which:

Figure 1 is a vertical longitudinal sectional view of the device showing a cigarette 30 mounted therein; and Fig. 2 is a side elevation of a cigarette showing the retaining sleeve mounted thereon preparatory to inserting the cigarette in the container. Fig. 3 is a perspective view of the sleeve.

Referring more particularly to the views, use is made of a holder 10 terminating at one end in a mouthpiece 11, the mentioned holder being tubular and provided with a 35 passage 12 enlarged at one end to form a seat 13 and a chamber 14 for an expandible spring 15. A tubular container 16 is threadedly mounted on an end of the holder 10 and the spring 15 is adapted to extend into the container 16, the free end of the container being provided with a peripherally 40 extending bead 17 forming a seat 18 for a retaining sleeve 19, the said sleeve 19 being adapted for engagement with the free end of the container, the said sleeve being preferably split and formed of a flexible material so that when the sleeve is mounted on the container the spring-like action of the material, together with the bead 17, will 45 retain the sleeve in rigid engagement with the container.

In the use of the device, the sleeve 19 is removed from the container 16 and the sleeve is then forced over the end of a cigarette 20, the mentioned end of the cigarette being first slightly compressed to receive the sleeve. The cigarette 20 is then inserted in the container 16 and pressed inwardly against the action of the spring 15, thus compressing the spring so that the same will be contained in the chamber 14, the retaining sleeve being adapted to engage the container with the inner end of the retaining sleeve adapted to engage the seat 18. It will now be seen that the tip end of the cigarette will lie within the retaining sleeve 19 and when the cigarette has been mounted in the container as mentioned the cigarette is lighted in the usual manner. Now as the cigarette 20 is consumed the action of the spring 15, pressing against an end of the cigarette, will force the ashes of the cigarette outwardly from the sleeve 19 and will also advance the cigarette in the container 16, so that almost the entire cigarette can be consumed and there will be no waste as is usually the case. It will also be seen that the sleeve 19 aids in retaining the cigarette within the container to prevent the spring from entirely forcing the unconsumed cigarette out of the container, and by providing 50 a device of the kind described for the accommodation of a cigarette, the action of drawing the smoke into the mouth will be easier in view of the fact that the cigarette will be almost entirely inclosed by the container 16, the device being also provided to prevent the fingers from becoming stained with tobacco.

Having thus described my invention, I claim:

1. In a device of the class described, the combination with a holder provided with a mouthpiece, of a container on the said holder and adapted to receive a smokable article, a spring carried in the holder and extending into the container to engage an end of the smokable article, a bead at one end of the container, and a split spring-like retaining sleeve for removable engagement with the container, the said sleeve being engaged by the said bead to retain the sleeve in engagement with the container.

2. In a device of the class described, the combination with a holder, of a container for removable connection therewith, a

spring in the holder and extending into the container, and a split spring-like retaining sleeve for removable engagement with the free end of the said container, the spring-like action of the split sleeve being adapted to normally retain the same in connection with the container.

In testimony whereof I affix my signature in presence of two witnesses.

PIERRE HUBERT HOUNGET.
